UNITED STATES PATENT OFFICE.

MICHAEL FAIX, OF PHILADELPHIA, PENNSYLVANIA.

COLLAPSIBLE CHAIR AND TABLE.

1,361,034.

Specification of Letters Patent. Patented Dec. 7, 1920.

Application filed March 10, 1920. Serial No. 364,722.

To all whom it may concern:

Be it known that I, MICHAEL FAIX, a citizen of the United States, and a resident of the city of Philadelphia, county of Philadelphia, and State of Pennsylvania, have invented certain new and useful Improvements in Collapsible Chairs and Tables, of which the following is a specification, reference being had to the accompanying drawing.

10 The invention relates to collapsible chairs and tables which when not in use or in transfer from one place to another or stored may be closed or collapsed into a comparatively small space and in a convenient form for 15 portability.

One of the objects of my invention is to provide new and useful tables and chairs of the type above indicated which may have the supporting surface thereof, such as the chair seat or table top detachably engaged with supporting members located beneath the same.

Another object is to provide the chair with a back or leaning support and side arms articulated thereto and to the chair seat in such 25 a manner as to fold with the rest of the chair construction into a compact form.

Other advantages and objects of my invention will appear more fully hereinafter.

30 Referring to the drawing upon which the same reference characters refer to the corresponding parts in the several views,

Figure 1 is a side view of a chair constructed in accordance with my invention;

35 Fig. 2 is a front view of the same, and,

Fig. 3 is an end or side view of a table constructed in accordance with my invention.

Referring now more particularly to the drawing I have shown therein (Figs. 1 and 40 2) a chair provided with the inner and outer supporting members 1 and 2 pivotally connected by a transversely disposed rod 3. A chair seat or supporting member 4 may be supported upon the members 1 and 2 by piv-

45 otally connecting the rear portion of the seat 4 upon the transverse rod 5, the latter being supported at the ends thereof in perforations provided in the upper ends in the side supporting members 2. The seat is supported

50 at its forward end upon a cross rod 6 also supported at the ends thereof in perforations provided in the upper ends of the side supporting members 1. The seat may be in the

form of a frame with the rod 6 passing longitudinally through the front transverse member 7 of the frame and the rod 5 passing similarly through the rear transverse member 8 of the frame, such members being connected by suitable slats or similar members 9 constituting the supporting portions of the seat. 60 This frame may also comprise connecting members 10 and 11 at the sides of the seat.

The frame portion 7 is preferably provided with an inclined notch 12 disposed or slanted downwardly toward the rear as is 65 clearly shown in Fig. 1, said notch being adapted to fit over the rod 7 so that upon the placing of a weight upon the chair seat force will be transmitted thereby to the supporting members 1 and 2 so as to enter and cause 70 the upper ends of the members 1 and 2 to separate. This action, however, will cause the rod 1 to remain seated in the notch 12 and by reason of the latter being inclined in the manner indicated there will be no 75 tendency for the rod 7 to work free therefrom, the inclination of the notch tending to insure maintenance of engagement between parts 7 and the rod 6.

At the rear of the chair between the upper 80 end of the supporting members 2 and the side frame members 10 and 11 are located the side pieces 13 and 14 of the back which may be pivotally mounted upon the rod 5 with the depending end 15 of the members 13 and 85 14 of proper length to be brought into engagement with the lower portions of the supporting members 1 and with the upper end of the back members 13 and 14 extending at a suitable height to form a back for the 90 chair. The side pieces 13 and 14 may be connected by transverse pieces 16, 17 and 18, the transverse piece 16 maintaining the lower extremity of the inside pieces 13 and 14 in proper relation to the supporting members 95 1 when engaging the same and the members 17 and 18 aside from maintaining the upper portions of the members 13 and 14 in proper spaced relation also functions to support the back of the sitter.

The lower portions 15 of the side pieces 13 and 14 form depending arms and the back support is arranged between the upper ends of the outer ends of the outer supporting members 2 and operate in the planes of 105 the inner supporting members 1 so that the

lower terminals of the arms 15 will abut against the rear edges of the inner supporting members 1. This will enable a common transverse pivot rod 5 to connect the seat, 5 the back support and the upper ends of the outer supporting members 2.

On the ends of the rod 6, adjacent the upper ends of the supporting members 1, may be pivotally connected at the lower ends 10 thereof, a pair of arm links 20, the latter being pivotally connected at the upper ends thereof, to the arm pieces 21. The arms 21 are also pivotally connected to the back pieces 13 and 14 by means of the pivot pins 15 22 and 23 respectively. The arms 21, as clearly shown in Figs. 1 and 2, may be suitably curved or bent to conform to the relative position of the parts connected thereto.

In use the chairs may be set up with the 20 seat brought into position so as to cause the rod 6 to enter the notches 12 thereof and with the supporting members in the position as shown in Fig. 1. At the same time the back may be drawn upwardly and back- 25 wardly until the lower portions 15 may contact with the lower portion of the supporting members 1, in which position the back of the chair will be in supporting position, the arm pieces 21 and the links 20 being 30 raised from collapsed position to the position shown in Fig. 1. When it is desired to carry the chair from place to place or to store the same, whereby it will not occupy as much space as when in use, the back may 35 be drawn forwardly so as to cause the same to lie approximately in the same plane as the seat of the chair with the link 20 drawn forwardly and the arms 21 located adjacent the lateral sides 10 and 11 of the seat frame. 40 The seat may then be disengaged from the rod 6 by causing the rod 6 to move out of the notches 12 and the supporting members 1, swung about the pivot rod 3 so that the members 1 may lie adjacent and substantially 45 parallel to the supporting members 2. These members may then be brought into approximately parallel position adjacent the bottom of the seat 4 by raising the supporting members 2, also carrying the members 1 therewith, about the pivot rod 5. In this 50 way the chair will occupy a small fraction of the space previously utilized.

It will be apparent from the above that the chair may be conveniently set up or 55 collapsed depending upon the use to which it is to be put, is comparatively simple in structure and convenient for portability as well as strong for supporting persons.

Referring to Fig. 3, I have shown therein 60 supporting members 1' and 2' pivotally connected by transverse rod 3'. Upon the supporting members may be supported a table top 4' constructed in any appropriate manner, as of boards or the like, suitably supported upon a pair of suitably spaced cross

pieces 9'. These cross pieces 9' may be pivotally mounted at the rear end thereof upon a transverse rod 5' suitably supported at the ends thereof in perforations provided in the upper ends of the supporting members 2' and pieces 9' may be provided at the forward ends thereof with inclined notches 12, slanted downwardly and rearwardly, adapted to engage with a transverse rod 6' supported at the ends thereof in perforations provided in the upper ends of the supporting members 1'. 75

In use the table top is supported upon the rods 5' and 6', as shown in Fig. 3, which in turn are supported at the ends thereof by the supporting members 1' and 2'. Any weight acting downwardly on the table has a tendency to cause a separation of the upper ends of the ends 1' and 2' and to cause the rod 6' to firmly seat in the upper end 80 of the notches 12'. By providing the notches in an inclined position the tendency of the rod 6' to move forwardly (to the right as shown in Fig. 3) causes the rod 6' to maintain its engaged position in the notches 85 thereby preventing any tendency of the table collapsing at a time when not desired.

When it is desired to carry the table from place to place or to store the same it is merely necessary to raise the table top so as 90 to disengage the rod 6' from the notches 12' and to permit the supporting member 1' to swing about the pivot rod 3' to a position adjacent and parallel to the supporting member 2'. The latter, with the members 1' in collapsed position with relation to the members 2', may then be brought into substantially parallel relation with the members 9' beneath the table top 4' by raising the same about the pivot rod 5'. 95

It may be observed that a table constructed in this fashion may be easily and quickly set up and collapsed, is conveniently portable and is strong for supporting heavy objects. 100

While I have herein described and shown upon the drawing certain embodiments of my invention, it is to be understood that the same is not to be limited to the particular details disclosed, but comprehends such changes and modifications as do not depart from the spirit of my invention and the scope of the appended claim. 115

Having thus described my invention, what I claim and desire to protect by Letters 120 Patent of the United States is:

A folding chair comprising oppositely inclined inner and outer crossed supporting members pivotally connected at the point of crossing and arranged in pairs, the outer 125 supporting members extending upwardly and rearwardly from the said pivotal connection, front and rear transverse pivot rods connecting the supporting members at the upper ends thereof, a back support arranged 130

between the upper ends of the outer supporting members and pivotally mounted on the rear pivot rod and provided with depending arms extending below the point of 5 crossing of the supporting members and having their lower ends abutting against the inner supporting members, and a seat

mounted on the rear pivot rod and provided at the front with means for detachably engaging the front pivot rod.

In witness whereof I have hereunto set my hand this 8th day of March, 1920.

MICHAEL FAIX.
